James G. Abbott & Archilus Lawrence of Philadelphia, Pa.
Letters Patent No 454 Dated April 27th 1852.

The schedule referred to in these Letters Patent and making part of the same

To all whom it may concern:

Be it known that we, James G. Abbott and Archilus Lawrence of the City and County of Philadelphia and State of Pennsylvania, have invented or produced a new and original design for Portable Furnaces, and we do hereby declare that the following is a full and exact description of the same, reference being had to the accompanying drawing forming part of this specification, in which

Fig. 1. is a Side Elevation.

Fig. 2. is a top view or plan.

The same letters of reference denote corresponding parts in both the figures.

A is the body of the furnace which consists of a fluted cylinder or column surrounded at the foot by a "hollow" moulding or cavetto B and headed by a circular cornice C enriched with semi or part globes a, and surmounted by an ornamental or fretted corona b.

The body of the furnace is provided with a lid or door D, in the front at its bottom, and rests on a platform which is of circular outline, for the greater part of the circumference of the body A but spreads to constitute an oblong table or hearth in front, left the corners forming obtuse angles with the sides of the table which bears in raised letters the title across it of

ABBOTT & LAWRENCE

PATENTED 1852.

The mouldings ornamenting the border of the platform consist of an ovol^e c. hollow d. ovol^e e. and fillet f. The whole structure is supported by circular pins or legs g cast to the platform or base.

A circular top or cover h is fitted loosely within the fretted corona b; this cover consists of a fluted concentric circle h, united to a plain outer circle or ring i. by eight curved fluted arms k. the outer ring i. having in raised letters, on or round its face, the words - "Liberty Stone" Works Brown St. above 4th St. Philadelphia"

The furnace is provided with a bail or handle l.

What we claim and desire to secure by Letters Patent, is The combination & arrangement of the Ornaments herein represented and specified, making an ornamental design for a Portable Furnace.
